United States Patent Office.

A. W. SHIDLER, OF SOUTH BEND, INDIANA.

Letters Patent No. 75,589, dated March 17, 1868.

IMPROVEMENT IN CIDER-PRESSES.

The Schedule referred to in these Letters Patent and making part of the same.

TO ALL WHOM IT MAY CONCERN:

Be it known that I, A. W. SHIDLER, of South Bend, in the county of St. Joseph, and State of Indiana, have invented certain new and useful Improvements in Cider-Presses; and I do hereby declare that the following is a full and complete description of the same, reference being had to the accompanying drawings, making part of this specification, in which—

Figure 1 is a side view of the press.

Figure 2, a view of the top.

Figure 3, a view of the front end.

Like letters of reference refer to like parts in the different views.

In fig. 1, A represents one side of an oblong square box, said sides being sawn through, making thereby a kind of slotted or open side, B, the bottom of which is also constructed in the same way, the ends and top being made tightly. C, fig. 2, is a head fitted to the inside of the box, and in which it is made to slide by means of the screw D to which it is attached. This screw passes through the end of the box, working in a nut, E, the outer end of the screw being supported by the stay F, fig. 3. G, fig. 2, are pipes, which are four in number, and arranged longitudinally within the box, in the order indicated by the dotted lines a, fig. 3. It will be obvious that the front ends of the pipes pass through the head, and are supported and kept in proper position thereby, and that the rear ends of the same are let into the end of the box, which also supports them and holds them in place. H is a vat or conductor arranged immediately under the box or press, and supported thereto by the cross-pieces I connecting the lower ends of the ports J, the upper ends being secured by the ties K, and which also serve to hold down the cover L, a portion of which is represented as being broken away in order to show the inside of the press.

Having thus described the construction and arrangement of the press, the practical operation of the same is as follows:

The head C is drawn up to the front end of the box. The pomace is then thrown in upon and around the pipes. The box, on being filled, the cover is then placed on and secured by the ties referred to. Now, on turning the screw, the head is forced back toward the rear end of the box, and is kept square and true in its movement back by the slides M, to which the stay supporting the screw is attached. By this application of the power of the screw the juice is quickly expressed, which flows through the sides of the box and bottom into the vat or conductor H. It also finds its way into the pipe through the numerous holes by which it is perforated, and thus the juice from the centre of the cheese is at once conducted away, without first having to pass through the pomace, as is the case in the ordinary press.

By this means much of the best portion of the juice is saved, which would otherwise be left in the pomace and thrown away.

The cheese is taken from the press by removing the end of the box, which is done by drawing out the keys or wedges A', which will allow the end to move back, away from the pomace. The end-board being released, can then be lifted from its place, and through the thus opened end of the box the cheese can be removed.

What I claim as my improvement, and desire to secure by Letters Patent, is—

The tubes G and head C, in combination with the perforated or open sides A, bottom B, and screw D, arranged and operating in the manner and for the purpose substantially as set forth.

A. W. SHIDLER.
